United States Patent Office

Des. 208,222
Patented Aug. 1, 1967

208,222

COMBINED CONTAINER BODY AND PULL STRIP OPENER

Edward John Slomski, Crystal Lake, Ill., assignor to American Can Company, New York, N.Y., a corporation of New Jersey

Filed Feb. 10, 1966, Ser. No. 992

Term of patent 14 years

(Cl. D58—26)

Fig. 1

Fig. 2

FIG. 1 is a bottom perspective view from one side;
FIG. 2 is a top perspective view from the opposite side; and

FIG. 3 is a fragmentary elevational view of the bottom portion of the present design.

I claim:

The ornamental design for a combined container body and pull strip opener, substantially as shown.
